UNITED STATES PATENT OFFICE.

WILLIAM WRIGHT, OF PLYMOUTH, COUNTY OF DEVON, GREAT BRITAIN.

BALL-VALVE OR REGULATOR.

SPECIFICATION forming part of Letters Patent No. 247,867, dated October 4, 1881.

Application filed April 11, 1881. (No model.) Patented in England March 2, 1881.

To all whom it may concern:

Be it known that I, WILLIAM WRIGHT, of Plymouth, in the county of Devon and Kingdom of Great Britain, have invented a new and useful Ball-Valve or Regulator, (for which I have obtained a patent in Great Britain, No. 899, bearing date March 2, 1881,) of which the following is a specification.

My improvement relates to that class of valve or regulator known as "ball-valve," the object of which is to shut off the supply of water or other fluid when the cistern or vessel to which it is applied has received a sufficient quantity. This is accomplished by the flotation power of

15 the hermetically-closed hollow ball.

My invention will best be explained by reference to the accompanying sheet of drawings, in which like letters represent like parts.

Figure 1 is a sectional elevation of the valve 20 and ball; and Fig. 2 shows a modified application of the ball, the valve remaining unaltered.

A is the hollow ball, of copper or other suitable material, through the center of which is inserted a tube, B, soldered or otherwise connected air-tight to the ball A. One end of tube 25 B is partly closed by a bridge or equivalent, B', by which the ball is connected to the valve, but is free to move up and down outside it.

The valve consists of an outer tube, C, having on the top the valve-seat C', through which the fluid enters by a suitable straight or curved branch, C''. The tube C may be screwed or otherwise attached to the branch and seating, as shown, or may form part of it, but the former plan is better. Within tube C is a smaller and generally longer tube, D, carrying on its upper end the valve D', of india-rubber, leather, or the like, or it may be made of metal and ground to fit the seat C'. The soft valve, 40 however, is less likely to leak if dirt or leaves get between the valve and seat, as not unfrequently happens. The upper end of tube D consists of a head, D², having suitable apertures, D³, for the entrance of the fluid to the 45 small tube, and a collar or washer, D⁴, fitting loosely inside tube C, so as to work freely within it. A loose washer, D⁵, is placed upon tube D, and between it and collar D⁴ is a piece of india-rubber tube, E, a helical spring or other 50 similar springy material which would be used

as a substitute for the india-rubber. The end of tube C is screw-threaded at C³, and into this screws a plug or gland, F, the edge of which may be "milled" or roughened to facilitate turning with the fingers, or squared for the spanner, and which may, if desired, be packed round tube D with a little cork, F', or equivalent, to make it slide nicely upon the tube. The projecting end of tube D screws into the ball-bridge B', as already described, and it will be noticed that it is immaterial to the working whether the ball projects upward so as to surround the valve or projects downward from the end of tube D, as shown in dotted lines in Fig. 1.

The arrangement of valve in Fig. 2 is precisely similar to Fig. 1, except that the ball is placed at the end of an ordinary lever, G, pivoted to a suitable bracket or attachment, C⁴, upon tube C, and split or divided, so as to embrace loosely tube D to which it is so connected that it will carry the tube up or down with it as it moves. The simplest way of doing this is by screwing the bottom of tube D into the lever G. When this arrangement is used the tube B may be dispensed with and the ball then 75 becomes an ordinary ball.

The action of this valve is as follows: The fluid enters through the branch C'', forcing back valve D', passes the seating and valve, and enters tube D through the holes D³, as shown 80 by the arrows. As the ball A rises it lifts tube D and valve D' till the opening is entirely closed and no more fluid can pass; but as the level of the fluid in the cistern or vessel sinks the ball drops with it and opens the valve again. The object of the spring or springy material E is to press up the valve D' against the seat and counteract the pressure of the fluid, so that 85 the ball shall have nothing to contend against except the slight friction and weight of the 90 valve or accessories.

The power of the spring E can be adjusted to a nicety by the plug F, so that a valve which has been working against a pressure of, say, one hundred pounds per square inch, can be 95 immediately regulated to suit a pressure of, say, four pounds, by merely turning the plug. However, the plug F could be dispensed with and a plain cap substituted, but then the pressure of the spring E would be constant and 100

could not be altered to suit circumstances; therefore I much prefer to use the regulating-plug. For shallow or small cisterns the plan with the ball turned up is best, as it takes up less room; but in some cases where there is plenty of height the ball may with advantage be turned downward, in which case the tube B may be, if desired, of smaller diameter than before; but if it be made so the ball is, of course, 10 not reversible. The lever arrangement shown in Fig. 2 is chiefly for the use of those who are accustomed to the usual form and prefer a long arm.

Having now described my invention, and 15 the method of performing the same, I wish it to be understood that I am aware that closing a valve by the flotation of an air-tight ball is no new idea, and therefore that I do not broadly claim the principle of closing valves in that 20 manner; but that

What I do claim, and desire to protect by Letters Patent, is—

1. In a ball-valve, the combination, with the ball A, having an axial tube, B, of the valve 25 spindle or tube D, to which said ball is directly

attached, and the valve D' and appliances, substantially as shown and described, for regulating said valve to work under various pressures, substantially as described, for the purpose specified. 30

2. In a ball-valve, the inner tube, D, attached at one end to the ball, and carrying at its other end the perforated head or its equivalent D², and valve D', in combination with the outer tube, C, valve-seat C', and supply-branch C², 35 substantially as and for the purposes set forth and shown.

3. The ball A, having an axial tube, B, the valve spindle or tube D, to which said ball is directly attached, and the valve and valve-regulating appliances contained within said axial opening or tube B, of the ball, substantially 40 as described, for the purpose specified.

4. In a ball-valve, the combination, with the valve-spindle and valve, of a reversible ball, 45 substantially as and for the purposes set forth.

WILLIAM WRIGHT.
